UNITED STATES PATENT OFFICE.

ELIHU C. WILSON AND WILLIAM W. WILSON, OF LOS ANGELES, CALIFORNIA,
ASSIGNORS TO SAID WILLIAM W. WILSON.

DESIGN FOR AN UNDERREAMER-CUTTER.

53,623.

Specification for Design.

Patented July 15, 1919.

Application filed September 27, 1916. Serial No. 122,578. Term of patent 14 years.

To all whom it may concern:

Be it known that we, ELIHU C. WILSON and WILLIAM W. WILSON, both citizens of the United States, residing at Los Angeles, in the county of Los Angeles and State of California, have invented a new, original, and ornamental Design for Underreamer Cutters, of which the following is a specification, reference being had to the accompanying drawing, forming part hereof.

In the drawing, Figure 1 is a front elevation, Fig. 2 is an inside elevation, Fig. 3 is

an outside elevation, and Fig. 4 is a plan view, each one showing our new design for underreamer cutters.

We claim:

The ornamental design for an underreamer cutter, as shown.

ELIHU C. WILSON,
WILLIAM W. WILSON.

Witnesses:

ALFRED H. DAEHLER,
L. S. ARNOLD.
